UNITED STATES PATENT OFFICE

BENJAMIN ZUCKERMAN, JR., OF NEW YORK, N. Y.

ENVELOPE SEALER

Application filed December 21, 1928. Serial No. 327,567.

This invention relates to an envelope sealer, and has for an object to provide an improved construction which may be applied to a wall or other supporter and which functions readily to seal envelopes of different sizes rapidly and efficiently.

Another object of the invention is to provide an envelope sealing device wherein means are presented for easily receiving and guiding the envelope and its flap so that the flap will be first moistened and then pressed to a sealed position.

A further object is to provide an envelope moistening and sealing device wherein the flap is guided over a moistening member while the body of the envelope is guided to the rear of the moistening member and out of contact therewith, the arrangement being such that the flap after moistening is automatically pressed to a sealed position.

In the accompanying drawings,—

Figure 1 is a perspective view of part of a wall with an envelope moistener and sealer shown in connection therewith, an envelope being shown mounted in the sealer;

Figure 2 is a longitudinal vertical sectional view through the envelope moistening and sealing device shown in Figure 1, the section being taken approximately on the line 2 of Figure 3;

Figure 3 is a transverse sectional view through Figure 2 approximately on the line 3—3;

Figure 4 is a perspective view of the water tank and certain associated parts;

Figure 5 is a perspective view of the resilient member used for guiding the flap against the moistening tape and for pressing the moistened flap to a sealed position.

Referring to the accompanying drawings by numerals, 1 indicates a wall or support of any desired kind, said wall or support carrying screws or nails formed with heads, said screws and nails being adapted to pass through the enlarged openings 2 and 3 in the casing 4 and then enter the slots 5 and 6, whereby the device is properly mounted on the wall. The casing 4 is provided with sides 7 and 8 and ends 9 and 10. The side 7 is provided with a notch 11 for receiving the

turned-over part 12 of the resilient guide and sealing member 13. End 9 is provided with raised portions 14 adapted to snap into the apertures 15 formed in the turned-down portion 16 which is an extension of the top 55 of the water container 17. The end 10 is formed with a projecting portion 18 for the full height of the end. This projecting portion is merely a bent part of the end which merges into the side 8, and thereby a guiding 60 groove 19 is presented for the edge of the envelope 20. It will be noted that the side 8 is spaced from the edge of the end 9 and also spaced from the wall 21 of the water container 17. The wall 21 is parallel with 65 wall 8 but the opposite side of the container is provided with walls 22 and 23 arranged at angles as shown in Figure 4, whereby there will be an edge 24 around which the flap 25 is adapted to extend while 70 the edge portion of the envelope is in the groove 19. Wall 23 merges into a clamping portion 26 for clamping the moistening structure or wick 27 against wall 21 and against the extension 28 of wall 21. 75

By constructing the parts in this way the body of the envelope which passes along the wall 21 is not brought in contact with the wick or moistening device 27, while on the other hand, the adhesive portion of 80 the flap is forced into contact with the tape or wick 27 by the section 29 or member 13. This member is bent at points 30 and 31, whereby the section 32 is positioned to resiliently press against the flap 25 for sealing the 85 same before the envelope leaves the device. By properly bending the guiding and sealing member 13 section 32 may press to any desired extent against the flap to always provide automatically a proper sealing medium. 90

Referring again to the container 17 it will be understood that the same is provided with a removable cap 33, whereby water may be inserted into the container from time to time. Also, when this cap is in place water 95 is fed from the container through capillary action and not through gravity, as the rarefaction in the upper part of the container will prevent an ordinary flow of water under the action of gravity. From Figure 4 100

it will also be noted that the top plate 34 which is integral with the portion 16 is formed with a raised guiding lug or extension 35 adapted to enter between the flap and body of the envelope as the edge of the envelope is first forced into the groove 19 and the body of the envelope is forced into the space or passageway 36 provided between the walls 8 and 21.

When it is desired to use the device the cap 33 may be grasped and the container 17 pulled out of the casing 4. This container is held in the casing 4 by the clamping action of member 16, which action may be readily overcome whenever desired. The container is then filled and replaced, or if preferred, it may be refilled without removal. After this has been done the device is ready for use and an envelope may be slid over the projection 35 and downwardly, as shown in Figure 1. From this position it is pulled further downwardly and in fact, pulled out the bottom of the casing 4. As the envelope moves downwardly the flap 25 strikes the surface 22 and then the surface 23 and finally is pressed by the portion 29 of the guide 13 against the wick or moistening device 27. The inclined portion 37 (Figure 2) finally guides the moistened flap back against the body of the envelope and the section 32 presses the moistened flap tightly in position as the envelope is pulled out the bottom of the device. It will thus be seen that the flap only is moistened and that means are provided for sealing the flap after the moistening operation.

What I claim is:—

1. An envelope sealer, comprising a casing, a bodily removable moistening device carried by said casing, said casing and moistening device presenting means for guiding an envelope, and a resilient member movably connected to said casing and positioned internally thereof for pressing the flap of the envelope against the moistening device and also for pressing the flap to a sealed position.

2. An envelope sealer, comprising a casing open at the top and bottom and provided with a slit at one edge for the full length thereof, a moistening device removably positioned in said casing and presenting a guiding wall for an envelope extending through said slit while the opposite wall of the slit is one side of the casing, said moistening device having a rounded projecting member for separating the flap of the envelope from the body, said moistening device having a moistening wick at the bottom thereof positioned to engage the adhesive carrying portion of the flap of said envelope as the envelope moves through the casing, and a resilient member formed with a portion for causing the flap to press against said wick, and a second portion for causing the flap to be pressed against part of the envelope.

3. An envelope sealer including a casing formed with a pasageway through which an envelope is adapted to be pushed and pulled, a water container removably mounted in said casing, means for removably securing said container to the upper part of said casing so that one wall thereof will be parallel to and adjacent one wall of said casing, a comparatively wide moistening tape carried at the lower end of said container, and means for causing the adhesive carrying portion of the flap of the envelope to move over said tape and in contact therewith, said means having a portion acting to press said flap against the body of the envelope.

4. An envelope sealer, including a casing, a water container positioned within said casing and acting as a guide for guiding an envelope through the casing, a resilient clip carried by said container positioned to normally hook over the edge of said casing for removably holding the container in said casing, a wick projecting from the lower part of said container and spring means acting in the double capacity of forcing the flap of the envelope against said wick and later forcing the flap against the body of the envelope.

5. In an envelope sealer, a rectangular casing open at the top and the bottom and having one side free from its adjacent edge, said free side having a loop at the point furthest from said edge, means for guiding and moistening an envelope as it passes through said casing, said means causing the part of the envelope where the flap and body join to extend into said loop, and means for pressing said flap to a sealed position as the envelope moves out of the casing.

6. In an envelope sealer, a casing through which an envelope is adapted to be passed, means in the casing for moistening the adhesive on the flap of the envelope, and a spring member acting as a guide and sealing member, said resilient member being formed of flat resilient metal having a hook at the upper end for removably holding the resilient member in the casing, a bent section for forcing the flap of the envelope against the moistening device, and a flat rubbing sealing section for resiliently forcing the flap against the body of the envelope after the flap has been moistened, whereby the flap will be sealed.

Signed at New York in the county of New York and state of New York this 19th day of December, A. D. 1928.
